UNITED STATES PATENT OFFICE

2,100,882

ELEVATOR GATE

Joseph C. Tamsitt, Aurora, Ill., assignor to Richards-Wilcox Manufacturing Company, Aurora, Ill., a corporation of Illinois

Application April 27, 1936, Serial No. 76,536

3 Claims. (Cl. 39—86)

The present invention relates generally to gates and particularly to gates for elevator cars or cabs, and the principal object of the present invention is the provision of a flexible gate of the 5 picket type that is adapted to be moved away from the elevator car opening and around the corner and along one side of the car itself.

Heretofore, gates of this general construction have usually been made up of a plurality of 10 pivoted or hingedly connected members, generally in the nature of rods and metallic hinges, all supported for individual pivot movement from suitable hangers movable along a track carried by the car. While such gates have generally 15 been fairly satisfactory, they are relatively heavy, expensive, involve many pivoted parts, hinge pins, and the like, and, moreover, have been noisy in operation.

One of the principal objects of the present 20 invention is the provision of a gate for an elevator car in which the picket members are rigidly connected with the associated hanger members and are connected together for relative folding or hinging movement, so as to pass around the 25 corner of the car, by one or more non-metallic flexible belts or bands which are securely clamped to the individual picket members. Such belt or band means, according to the principles of the 30 present invention, is in the nature of a relatively sturdy band or bands of rubber and fabric or the like, which, while securely holding the picket members in proper position, possesses sufficient flexibility so that all articulated joints, hinge pins and the like can be eliminated, rendering 35 the gate light in weight and smooth and silent in operation, but without detracting from either the appearance or the strength of the gate.

Another object of the present invention is the 40 provision of improved guide means for a gate of this character, involving nonmetallic members carried at the lower end of each of the picket members and movable in a suitable channel guideway in the car. Since the lower members, 45 movable in the associated guideway, are non-metallic, very little if any noise is created by the opening and closing of the elevator car gate.

Another object of the present invention is the provision of a new and improved picket member 50 for said gates, specifically a hollow rod of suitable cross section receiving a hanger strap at its upper end and carrying a nonmetallic guide member at its lower end disposed within the hollow picket member.

55 These and other objects and advantages of the

present invention will be apparent to those skilled in the art after a consideration of the following detailed description of the preferred embodiment, taken in conjunction with the accompanying drawings illustrating such embodiment. 5

In the drawings:

Figure 1 is a perspective view of an elevator car or cab equipped with a gate constructed according to the principles of the present invention; 10

Figure 2 is a section taken through the gate substantially along the line 2—2 of Figure 1;

Figure 3 is a horizontal section taken along the line 3—3 of Figure 2;

Figure 4 is a horizontal section taken through 15 a portion of the elevator car or cab substantially along the line 4—4 of Figure 1;

Figure 5 is a view similar to Figure 2 but showing a modified form of gate picket construction; and

Figure 6 is a section taken along the line 6—6 20 of Figure 5.

Referring now to the drawings, more particularly to Figure 1, the elevator car or cab is indicated in its entirety by the reference numeral 1 and includes a roof 2, side panels 3 and 4, and a 25 floor or bottom 5, of a more or less conventional construction. The floor 5 includes a guide channel 7, which will be referred to later, and the side panel 4 includes a section 4a disposed at the front side of the car and to one side of the opening 8 in the front of the car by which access to the latter is had. Across the top of the opening 8 and along the upper portion of the side panel 4 of the car are angled plate sections 11 and 12 30 to which the supporting track is fastened. 35

The elevator gate is indicated in its entirety by the reference numeral 20 and includes a track 21 supported in any suitable manner on the elevator car or cab and a flexible picket section 22 including vertical members connected together by flexible bands 23, which may be formed of rubber and fabric or the like. The track construction, best shown in Figure 2, includes a plurality of brackets 25, each in the form of a bracket plate 26 secured by rivets 27 or the like to the angle members 11 and 12 and serving to support a track rail 28 in spaced relation by means of a spacer sleeve 30 secured to each of the bracket plates 26 by means of a rivet 31 or the like. The supporting edge 32 of the track rail 28 is rounded as best shown in Figure 2, and as best shown in Figure 1, stop lugs 35 and 36 are provided at the ends of the track rail 28, the latter being disposed over the cab opening 8 40 45 50 55 60 65 70 75 80 85 90 95 98 99 100

and bent so as to lie along the upper edge of the side panel 4.

The flexible picket section 22 includes a plurality of vertical picket members 39, each rigidly connected at its upper end to a supporting hanger member 40. As best shown in Figure 2, the preferred form of hanger includes a strap which has an inwardly bent lower section 41 rigidly secured to the upper end of the associated picket member 39 by any suitable means, such as screws 42, and above the strap section 41 the hanger is bent as at 43 and at its uppermost end terminates in an inverted U-shaped yoke 44, the terminal end 45 of which extends downwardly and lies substantially in or adjacent the plane of the picket member 39 and the lower picket receiving portion 46 of the hanger strap. The inverted U-shaped yoke section 44 carries a bearing rivet 50 which, in turn, supports the inside and outside cones 51 and 52 upon which the top roller 53 of the hanger is rotatably mounted, as by anti-friction ball bearings 55. The bottom roller 56 is supported on a rivet 57 similar to the rivet 50 mentioned above, the rivet 57 also supporting inside and outside cones 62 and 63 upon which the roller 58 is mounted for rotation, as by ball bearings 65. The upper or top roller 53 has a curved load supporting surface which cooperates with the curved load receiving edge of the track rail 28, while the lower roller has a deeper flange and functions principally to keep the hanger in position on the track. Each of the hangers 40, both end and intermediate hangers, is of the same construction as described above, and hence further description is not necessary.

In the form of the invention shown in Figures 1 and 3, the several vertical picket members 39 are solid in cross section, as best shown in Figure 3, and are preferably formed of aluminum, so as to be strong but light in weight, but any other metal may be used if desired.

A guide shoe is carried at the lower end of each of the picket members 39, as indicated by the reference numeral 70. Each of the guide shoes 70 consists of a block of nonmetallic material, preferably a phenolic condensation product, and is rigidly secured to the lower end of the associated picket 39 by means of screws or rivets 71. The members 71, as well as the members 42, may if desired be self-tapping screws. The lower ends of the several bottom guide shoes 70 are formed to be movably disposed in the guide channel 7, and as best shown in Figure 4, the guide channel 7 is formed in the floor or platform of the car in any suitable manner. Stop lugs 75 and 76 (Figure 1) are carried at the ends of the guide channel substantially underneath the stop lugs 35 and 36 on the top rail 28 and cooperate with the end picket members 39 in limiting the open and closed position of the gate 28.

The picket members 39 are connected together for relative movement in spaced relation by means of three flexible bands 23, mentioned above. Each of the belts may consist of a band 65 of vulcanized rubber and fabric, somewhat similar to rubber tire stock and possesses considerable strength but is quite flexible, or the bands may be formed of any suitable non-metallic material. The bands 23 are rigidly clamped to each 70 of the vertical picket members 39, or between the pickets if double pickets are used, by any suitable means that insures the firm attachment of each of the picket members to the belts. Preferably, as best shown in Figure 3, the bands 75 are clamped thereto by means of clamping bars

88 and self-tapping screws 81 or the like. When the screws are driven home, the clamping bars firmly hold the bands to the picket members 39. For those pickets which are disposed adjacent the front panel section 4a of the car when the gate is open, the clamping bars are replaced by stiffener plates 85 which, in the form illustrated, extend over four of the picket members and are firmly secured to each bar by self-tapping screws 86 or the equivalent. Since these picket members never pass around the corner of the car, they need not be flexibly connected together for relative movement, but such relative movement is necessary for the remainder of the picket members, as will be obvious from Figure 1, since this portion of the gate must pass around the corner of the car, being guided in this movement by the upper track rail 28 and the lower guide channel 7.

The use of picket members in the form of solid bars may not in all cases be desirable. In Figures 5 and 6 I have illustrated the use of tubular picket members and a somewhat different form of connection between the picket members 90 and the associated hanger and guide members. Referring now to Figures 5 and 6, the reference numeral 90 indicates a tubular picket member of hollow construction, preferably formed of sections 91 and 92 fabricated as indicated in Figure 6. The hanger unit 93 is of substantially the same construction as described above, except that the upper inverted U-shaped yoke section has been eliminated and the upper roller 53 supported on one end of a rivet 94 placed at the upper end of the hanger strap 95. The lower end of the hanger strap 95 is bent inwardly, as at 97, and is inserted into the upper end of the hollow tubular picket member 90, and secured therein by rivets or screws 98. At the lower end of the tubular picket, the guide member 101, which is preferably formed of the same material as the guide members or shoes 70 described above, is formed so as to be capable of being inserted into the open lower end of the tubular picket member 90, and secured therein by screws or rivets 102. The guide shoes 101 move in the guide channel 7 in the floor of the car and serve the same purpose as set forth above in connection with the form of the invention shown in Figure 1. To facilitate their movement in the guide channel 7, the nonmetallic guide shoes 70 and 101 are both provided with rounded corners as indicated at 105.

While I have thus shown and described above the preferred structure embodying the principles of the present invention, it is to be understood that my invention is not to be limited to the specific details shown and described above, but that, in fact, widely different means may be employed in the practice of the broader aspects of my invention.

What I claim, therefore, and desire to secure by Letters Patent is:

1. In an elevator gate of the around-the-corner type, a plurality of vertically disposed bars spaced apart in the direction of gate travel, and a plurality of flexible non-metallic horizontal bands of sound deadening material connected to the bars and having sufficient thickness to maintain the bars in spaced apart relation and to prevent being kinked in operation.
2. In an elevator gate of the around-the-corner type, a plurality of vertical members spaced apart in the direction of gate travel, a plurality of horizontal non-metallic bands of flexible sound dead-

ening material rigidly clamped to said vertical members, and non-metallic guides carried at the lower end of each of said vertical members.

3. In an elevator gate of the around-the-corner type, a plurality of vertically disposed bars spaced apart in the direction of gate travel, a plurality of flexible non-metallic horizontal bands of sound deadening material connected to the bars and

having sufficient thickness to maintain the bars in spaced apart relation, and a stiffener plate for each flexible band disposed over and serving to connect substantially all of the vertical bars that, in the open position of said gate, are disposed adjacent the front of the elevator. 5

JOSEPH C. TAMSITT.
